UNITED STATES PATENT OFFICE.

JOHN LALLY, OF BOSTON, MASSACHUSETTS.

BEAM HANGER.

Application filed February 20, 1923. Serial No. 620,231.

To all whom it may concern:

Be it known that I, JOHN LALLY, a citizen of the United States, residing at Boston, in the county of Suffolk and State of Massachusetts, have invented certain new and useful Improvements in Beam Hangers, of which the following is a specification.

My invention relates to beam brackets intended to replace mortises and tenons in setting floor joists into headers in building operations and it is my object to so construct and utilize my brackets that sagging of the joists will be prevented and greatly increased load carrying capacity will result. Another object is to utilize ordinary rolled stock in making the brackets and to provide means for preventing the cutting of the wood in the headers and joists and for more effectually tying the two together.

In the drawing Fig. 1 is a side view showing the preferred form of my bracket let into the top of a header; Fig. 2 a like view of a modification of the preferred form let into the side of a header; Fig. 3 a side view of one form of my bracket; Fig. 4 a top view of the structure of Fig. 3; Fig. 5 a detail view of a bushed header hole with my bracket inserted; Fig. 6 a side view of a bracket with a spike end adapted to be driven into a header; and with a flattened surface to contact with the joist; Fig. 7 a side view of my bracket with a metal bearing plate under the joist; Fig. 8 detail view of my bracket with the bearing plate inset into the joist; Fig. 9 a detail view of a metal bearing plate; Fig. 10 a side view of my bracket in conjunction with bottom plates used as a tie between the header and joist; Fig. 11 a bottom view of the structure of Fig. 10; Fig. 12 a side view of a modified form of the construction with a special form of tie plate; Fig. 13 a bottom view of the structure of Fig. 12; Fig. 14 a modified construction in which the hanger enters the face instead of the top of the header; Fig. 15 a front view of the structure of Fig. 14; and Fig. 16 a sectional detail of the hanger end and bushings of the structure of Figs. 15 and 16.

Heretofore most joist carrying brackets have been simply hung over the header and unless they have been extra heavy have, in time, bent at the angles and allowed the joist to drop resulting in a sagged floor. This has been, to a large extent, a source of weak-

ness and various efforts have been made to overcome this defect. I have found that if rolled stock, preferably a round bar, which gives strength with lightness, is bent into bracket form and set into the header itself instead of merely straddling it the joist will not sag and the strength of the floor is greatly increased. I attribute this to the fact that the portion of the bracket within the header is supported on all sides instead of being free to bend in one direction when the load comes on it.

In the drawings 1 is the header and 2 is the joist. While I use the terms "header" and "joist" herein I do not limit myself thereto as my improved building construction may be used to join any two timbers at an angle to one another for load carrying purposes.

The bracket consists essentially of a bottom bar approximately the width of the joist to be varied, side bars between which the joist is adapted to lie, top bars lying on top of the header and hooked ends entering apertures in the top face of the header, or, in the alternative the top bars enter directly into apertures in the side of the header, the hooked ends being omitted.

My preferred form of hanger is shown in Fig. 1 in which the side bars 4^a-4^a are straight down between 19 and 20 to lie against the header 1 and are bent forward at 20 to give additional bearing to the joist 2. Tests have shown that the hanger stretches down from the point 19 to the point 22 and that the load has a tendency to raise the hooked in portion of the hanger 17 if the side arms are straight from 19 to 22 but the forward bend at 20 produces a square pull down at 17, 18, 19 and 20 which prevents the hooked part 17 pulling out as readily as it would, for example, in using the form of side bars shown in Figs. 3 to 16.

A further advantage resulting from the forward bend at 20 is that in positioning the hanger the arm can be rested against the side of the header and the holes marked for accurately boring the holes to receive it as the sides of the hanger between 19 and 20 will act as guides. If spike ends are used as shown in Fig. 6 the parts between 19 and 20 act as guides and can be held tightly against the header face while the spikes are driven down into the header.

The hanger shown in Fig. 2 also has the

bent side arms and has advantages in strength over the straight form as the arms of the hanger line up part way against the face of the header thereby reducing the tendency of the part 16 to pull out of its bushing or socket as the straight downward pull exerted between the points 19' and 20' eliminates the outward pull. The face of the header also acts as a guide for the straight part of the arm from 19' to 20' and controls the position of the hanger.

As before stated the header 1 is counter-bored in its top face to receive the hooks 6-6 and the top bars 5-5 rest on a bearing plate 7 secured to the upper face of the header to prevent cutting of the wood and to distribute the load. In Figs. 3 and 4 I have shown a metal bearing plate 8 set into the under side of the joist to contact with the bottom bar 3 of the bracket to prevent the bottom bar cutting into the joist and another bearing plate 9 against the lower part of the side of the header to contact with the lower corner of the joist to prevent its cutting into the header.

In the structure of Fig. 5 the hooks 6-6 are set into metal bushings 10 in the apertures to prevent enlargement of the holes in the header.

In Fig. 6 I have shown a modified form of bracket in which the ends of the hooks 6'-6' are spikes to enable them to be driven into the header and the sides and bottom bar of the round bar stock are forged into flat faces to receive the joist.

In Figs. 7, 8 and 9 I have shown how the bottom bearing plate 8' may be in the form of a piece of rolled channel section metal, in the channel of which the bottom bar sits. In Fig. 7 this is shown below the joist and in Fig. 8 as inset into the joist. In Fig. 9 I have shown how the ends of the bottom bearing plate may be notched to receive the side bars of the bracket to prevent slipping of the plate.

In the form shown in Figs. 10 and 11 the bottom plates 12-12 lie under and extend beyond the bottom edges of the joist 2 and are notched to receive the hanger sides and also extend under the header. These plates 12-12 are secured to both the header and joist to anchor them more solidly together.

In the form shown in Figs. 12 and 13 the bottom plate 13 is punched from sheet stock and has a V-notch at one end and a corresponding V-point at the other end and is used to join up the joist and header. In this form of bottom plate a minimum of metal is used as the V-point of one plate is cut from the V-notch of the next one in the sheet.

In the form shown in Figs. 14, 15 and 16 the hanger is let into the face of the header instead of the top. That face of the header 65 is apertured and half-circle metal bushings

14-14 are inserted therein. The hanger is preferably of half round rolled stock and with an end 5' entering the bushed hole in the header. A half round plug 15 is then driven into the bushed hole to anchor the 70 hanger end therein. The hanger has the bottom bar 3' and side bars 4'-4' and functions in the same manner as the hangers of the other figures, the end pressure of the joist aiding in holding the hanger ends in 75 the counterbores in the header.

The bent side arms shown in Figs. 1 and 2 may be used in lieu of the straight side arms shown in Figs. 3 to 16, in which event greater security is obtained by driving a 80 pin 21 into the joist at the point 20 where the bend occurs.

The advantages of my hanger over other types is that the material can be procured at any ordinary steel stock yard. The material is concentrated so that it is less susceptible to heat in case of fire. There is less area of material because of concentration where the load has the greatest effect, because of the greater resistance of the 90 hanger thereby preventing crushing of the header at the corner where it is always the weakest, because of the reduced weight over the same safe carrying capacity of other hangers, because it is made of rolled 95 sections and not cast, it being well known that rolled sections are more reliable than cast shapes. My invention therefore embodies efficiency and economy.

The essential features of my invention 100 reside in inserting the hooks or their equivalent fastening means into the body of the header instead of merely straddling it and in providing metal bearing plates at points likely to be cut into under load which would 105 allow the joists to sag. Also the forward bend in the side arms intermediate their lengths to get a solid bearing against the face of the header and allow the bottom bar to engage the under face of the joist at a 110 distance from its end.

I claim:-

1. Building construction comprising an apertured header, a joist, a bracket formed with a bottom bar carrying the joist, side 115 bars between which the joist lies and ends entering apertures in the header and bearing plates interposed between the hanger and the header and joist.

2. Building construction comprising a 120 header apertured in its upper face, a joist, a bracket formed of round section metal with a bottom bar carrying the joist, side bars between which the joist lies, top bars resting on the top of the header and hooks extending into apertures in the header, said bottom and side bars being flattened where they contact with the joist.

3. Building construction comprising a 130 header apertured in its upper face, a joist,

a bracket formed with a bottom bar carrying the joist, side bars between which the joist lies, top bars resting on the top of the header, hooks entering apertures in the header and a metal plate on the header under the bracket top bars.

4. Building construction comprising a header, apertured in its upper face, a joist, a bracket formed with a bottom bar carrying the joist, side bars between which the joist lies, top bars resting on the header, hooks extending into the apertures and a metal plate between the joist end and header side.

5. Building construction comprising an apertured header, a joist, a bracket formed with a bottom bar carrying the joist, side bars between which the joist lies, ends entering apertures in the header and a bearing plate interposed between the bracket bottom bar and the joist said plate extending under the header and secured to the header and joist.

6. Building construction comprising an apertured header, a joist, a bracket formed with a bottom bar carrying the joist, side bars between which the joist lies, ends entering apertures in the header and a bearing plate interposed between the bracket bottom bar and the joist and extending under the header and secured to the header and

joist, one end of said plate having a V-point and the other end a V-notch.

7. Building construction comprising a header, bushings in apertures therein, a joist, a bracket formed with a bottom bar carrying the joist, side bars between which the joist lies and ends entering the apertures and wedges driven into the apertures to secure the bracket ends therein.

8. Building construction comprising a header apertured in its upper face, a hanger consisting of side bars adapted to contact with the header for a portion of their length, said side bars being bent forwardly away from the header and finally bent across to form a bottom bar on which the joist is adapted lie between the side bars.

9. Building construction comprising a header, a hanger secured thereto provided with side bars contacting with the face of the header for a portion of their length and bent forwardly away from the header at their lower parts and a bottom bar, a joist lying on the bottom bar and between the side bars and pins driven into the joist at the bends in the side bars.

In testimony whereof I have affixed my signature.

JOHN LALLY.
